DESIGN FOR A PIN

James J. Poland, Providence, R. I., assignor to Goldstein-Poland Co., Inc., Providence, R. I., a corporation of Rhode Island

Application April 8, 1941, Serial No. 100,228

Term of patent 3½ years

To all whom it may concern:

Be it known that I, James J. Poland, a citizen of the United States, residing at Providence, in the county of Providence and State of Rhode Island, have invented a new, original, and ornamental Design for Pins, of which the following is a specification, reference being had to the accompanying drawing, forming part thereof wherein,

Fig. 1 is a front elevational view of the pin, and,

Fig. 2 is a top plan view of the same, as seen when looking downwardly upon the pin as shown in Fig. 1.

I claim:

The ornamental design for a pin or similar article, substantially as shown.

JAMES J. POLAND.
